FRITZ VÖSTER AND MAX JUNGBAUER, OF AUGSBURG, GERMANY, ASSIGNORS TO COOK AND CO., OF MANCHESTER, ENGLAND, A FIRM.

CARDING-ENGINE.

1,103,231.

Specification of Letters Patent. Patented July 14, 1914.

Original application filed December 27, 1908, Serial No. 535,093. Divided and this application filed March 29, 1911. Serial No. 615,463.

To all whom it may concern:

Be it known that we, FRITZ VÖSTER and MAX JUNGBAUER, both of Augsburg, Germany, have invented certain new and useful 5 Improvements in Carding-Engines, of which the following is a specification.

This invention relates to apparatus for 10 cleaning the card clothing of carding engines by suction and its object is to provide improved means whereby the card clothing may be cleaned or "stripped" by suction alone without the assistance of rotating brushes or air under pressure as has hitherto been proposed.

15 It is well known that in the process of "carding" textile fibers the short angular wires of the carding engine cylinders become clogged with fibers or impurities which must be removed periodically. This removal of 20 all impurities that become embedded in the card teeth is called "stripping."

Carding engines usually employ a main carding cylinder and a doffer; it is the main cylinder that actually performs the carding 25 operation, while the doffer merely removes the carded fibers from the points of the teeth of the main cylinder. This difference of function causes the matter embedded in the teeth of the cylinder and doffer to differ very 30 considerably; *i. e.*, the material that clogs the teeth of the main cylinder consists of seeds, leaf and short-staple cotton, and these materials become very firmly matted and embedded in the wires of the card clothing 35 and are therefore very difficult to remove satisfactorily. The material that clogs the teeth of the doffer is of a very different nature—particularly all of the heavier impurities (leaf, seeds, etc.,) having been removed by the main cylinder—and consists almost entirely of short-staple cotton and dust, which is not very firmly embedded and therefore is not difficult to remove, this being due, as stated above, to the work of the 40 doffer, *viz.*, the removing of the already carded fibers from the main cylinder.

Prior to the present invention rotating 45 brushes were used to remove the embedded materials from the teeth of the card cylinder. In this operation the fibrous portions of the embedded material clung to the wire teeth of the brush, but the greater bulk of the heavier portions of the embedded materials and the whole of the dust were

thrown into the atmosphere, which was thus 55 polluted. Many attempts have heretofore been made to utilize suction for collecting the materials (dust, leaf, and seeds) thrown into the atmosphere by rotary brushes; in some cases suction nozzles have been arranged 60 near the brush, but such constructions have had no commercial success; in other cases the brush has been inclosed in a canopy or hood to catch or retain the dust, etc., which was then carried away 65 through suction pipes connected to the interior of the hood, and such arrangements, although removing the dust, have not obviated the disadvantages of the rotary stripping brush. The chief of these disadvantages are:—

(1.) It is impossible to clean the carding surface of the cylinder completely with a brush. The carding surface consists of bent wires usually set in a rubber-faced fabric 75 and if the rotary brush were set deep enough to reach the fabric in which the teeth are fixed the said fabric would be injured permanently.

(2.) The wires or teeth of the card clothing are bent at an obtuse angle, so the rotary brush besides blunting the points is liable to injure the wire teeth themselves and to loosen them in the fabric in which 80 they are mounted.

(3.) It is impossible to use a rotating brush while the cylinders are rotating at full speed. The carding engine must be stopped, and the cylinder subsequently rotated slowly 85 while the stripping brush is being applied. From this it will be gathered that it is much more difficult and also much more important commercially to clean the main cylinder 90 than it is to clean a doffer; a doffer could be easily stripped in several ways, but the 95 cleaning of the main cylinder was for years a difficult matter.

One of the objects of the present invention is to provide means whereby the carding cylinder may be cleaned by suction while 100 the same is running at full speed.

A further object is to provide means for providing a suction opening of small volume and for shifting the same so as to traverse the entire cylinder surface.

105 The invention will be hereinafter fully set forth and particularly pointed out in the claims.

In the accompanying drawings Figure 1 is a diagrammatic side elevation of a carding engine showing one way in which the improvements may be applied; Fig. 2 is a front elevation, partly in section, of the traverse mechanism, the nozzle being shown in cross section; and Fig. 3 is a side elevation showing a portion of the card clothing and the suction nozzle with certain parts 10 of the traverse mechanism therefor.

A is a carding engine of which *a* is the frame, *c* the cylinder, and *d* the doffer; *N* are suction nozzles, which are connected by means of flexible pipes *f* to rigid pipes *p* leading to a collecting box *F* which is, in turn, connected to a vacuum pump *P*; and *T* are traverse mechanisms which are arranged parallel with and adjacent to the carding surface *b* of the engine.

20 Each nozzle *N* is mounted upon a carriage *t* which consists of a collar provided with a guide pin adapted to engage with a double-threaded screw *s*; the said carriage slides upon a fixed tube *u* which incloses the screw *s* and which is formed with a longitudinal slot through which the guide pin projects in order to engage with the threads of the screw *s*, rotation of the carriage upon the tube *u* being thereby prevented. Suitable 25 means, not shown in the drawings, are provided for rotating the screw *s* and thus causing the carriage *t* and nozzle *N* to reciprocate in front of the card clothing *b*.

The operation is as follows: While the 30 carding engine cylinder is in motion the nozzle *N* is traversed across the carding surface *b*, the pump having been set in operation. The result is that, owing to the high pressure suction set up and maintained by 35 the pump, and the relatively small volume of the suction nozzle the fibers, neps, dust, and other foreign matter embedded in the card clothing *b* are drawn through the nozzle *N*, effectively cleaning the card clothing *b* as indicated in Fig. 2, while the fibers, naps, dust and other foreign matter are 40 collected and prevented from getting into the pump by the filtering action of the collecting box.

This application is a division of our pending application, Serial Number 535,093, 50

Having now described our said invention what we claim and desire to secure by Letters Patent in the United States, is:

1. In a carding machine, the combination 55 of a screw extending entirely across and parallel with the carding surface, a suction nozzle of small volume mounted on the screw, means for rotating the screw to move the nozzle longitudinally therein, and means for creating a suction in said nozzle.

2. In a carding machine, the combination with the carding surface thereof, of a suction nozzle of small volume, means for moving the nozzle entirely across said surface 65 in a plane parallel therewith, and means for creating a suction in said nozzle.

3. In a carding machine, the combination with the carding surface, of a fixed sleeve 70 extending entirely across said surface and provided with a longitudinal slot extending along the whole working breadth of the carding surface, a screw rotatable in the sleeve, a nozzle of small volume slidable on the sleeve and having a pin projecting 75 through the slot and engaging the screw, and means for creating a suction in the nozzle.

4. In a carding engine the combination with the carding surface thereof, of suction 80 means provided with a suction opening of small volume opposite said surface, and means for causing said suction opening to traverse said carding surface irrespective of the speed of movement of the latter. 85

5. The combination, with the main cylinder of a carding machine of an air nozzle of small volume directed against the idle side of said cylinder, means to produce a suction current through said nozzle, and means to 90 traverse said nozzle progressively to all parts of said cylinder as the latter rotates.

FRITZ VÖSTER.
MAX JUNGBAUER.
